DESIGN FOR A BOTTLE HOLDER OR SIMILAR ARTICLE

Philip B. Arnold, Cleveland Heights, Ohio

Application July 27, 1939, Serial No. 86,263

Term of patent 7 years

To all whom it may concern:

Be it known that I, Philip B. Arnold, a citizen of the United States, residing in the city of Cleveland Heights, county of Cuyahoga, and State of Ohio, have invented a new, original, and ornamental Design for a Bottle Holder or Similar Article, of which the following is a specification, reference being had to the accompanying drawing, forming a part thereof.

The figure is a perspective view of the bottle holder or similar article showing my new design.

I claim:

The ornamental design for a bottle holder or similar article, substantially as shown.

PHILIP B. ARNOLD.
